UNITED STATES PATENT OFFICE.

OLIVER WARREN JOHNSON, OF OAKHARBOR, OHIO.

CAR-REPLACER.

SPECIFICATION forming part of Letters Patent No. 710,584, dated October 7, 1902.

Application filed January 25, 1902. Serial No. 91,227. (No model.)

To all whom it may concern:

Be it known that I, OLIVER WARREN JOHNSON, a citizen of the United States, residing at Oakharbor, in the county of Ottawa and 5 State of Ohio, have invented certain new and useful Improvements in Car-Replacers; and I do hereby declare the following to be a full, clear, and exact description of the invention, such as will enable others skilled in the art to 10 which it appertains to make and use the same.

The purpose of this invention is the provision of a new and effective device to assist in replacing a derailed car, the appliance being comparatively light, so as to be easily 15 handled, and with all durable and strong, so as to withstand the strain and weight attendant upon its use.

A further purpose of the invention is the construction whereby the replacer may be 20 used upon either rail of the track without necessitating the provision of rights and lefts, although the latter construction is contemplated, and in some instances a pair consisting of rights and lefts will be provided for 25 simultaneous operation upon opposite wheels of the same truck.

For a full description of the invention and the merits thereof and also to acquire a knowledge of the details of construction of the 30 means for effecting the result reference is to be had to the following description and drawings hereto attached.

While the essential and characteristic features of the invention are susceptible of modification, still the preferred embodiment of the 35 invention is illustrated in the accompanying drawings, in which—

Figure 1 is a side view of a car-replacer embodying the invention, showing it in operative relation. Fig. 2 is a top view. Fig. 3 is a view of the replacer inverted. Fig. 4 is a central longitudinal section on the line X X of Fig. 2. Fig. 5 is a rear view. Fig. 6 is a front view.

40 Corresponding and like parts are referred to in the following description and indicated in all the views of the drawings by the same reference characters.

The replacer is approximately of V form 45 and comprises wings 1 and 2, located upon opposite sides of a longitudinal slot 3, through

which the rail 4 extends when the device is in position, as shown most clearly in Figs. 1 and 4. The appliance curves longitudinally and is reinforced by pendent ribs 4 and 5 and 55 flanges 6, 7, 8, and 9. The rib 5 is straight, whereas the rib 4 is curved. The flanges 7 and 8 are located upon opposite sides of the slot 3 and are adapted to come upon opposite sides of the rail 4 and brace the device laterally as well as perpendicularly. A guard 10 is provided upon the top side of the wing 1 adjacent to its outer edge and is flat upon its top side and gradually widens from the base of the replacer toward the smaller end. 60 A space 11 is provided between the front end portions of the parts 6 and 10 to receive the flange of the wheel as the latter is about to pass upon the track after being elevated and directed to proper position. The upper surface of the device between the guard 10 and flange 6 is straight transversely, but gradually curved longitudinally, so as to elevate the car-wheel as the car is moved forward. The lower edge of the device is cut away adjacent to the slot 3, as shown at 12, so as to 65 clear the base of the rail when in position. Lugs 13 are provided upon the lower side of the replacer near its rear end and adjacent to the sides of the slot 3 and are adapted to 70 engage over the heads of spikes driven into a cross-tie, so as to prevent slipping when a car is being moved over and upon the replacer. The front ends of the flanges 6 and 9 are parallel for a short distance and come 75 upon opposite sides of the head of the rail and prevent any lateral movement of the appliance when in operation.

When in position, the front portion of the device rests upon the rail and is elevated a 80 short distance above the road-bed, whereas the rear end rests upon a tie. By having the replacer curved longitudinally and adapted to be supported at its front end solely by means of resting upon the rail a minimum 85 amount of material may enter into its formation, as it is not necessary to extend the front portion so as to obtain a purchase upon a tie or the road-bed, as is the case with devices of this kind as generally constructed. Lateral 90 displacement of the device is prevented by the longitudinal flanges 7 and 8 embracing

opposite sides of the rail and by the rear portion of the device straddling the rail which passes through the slot 3, as will be readily comprehended. The rear end of the replacer is constructed to obtain a firm and broad bearing upon the tie, so as to withstand the perpendicular pressure and prevent any turning of the article when in place and in service. Lugs 14 are pendent from the rear corner portions of the device to enter a tie and materially assist in holding the appliance in place. These lugs extend crosswise of the contrivance and are comparatively narrow and taper to an edge, so as to readily penetrate the tie. The cut-away parts 12 enable the rear portion of the replacer to obtain a bearing upon the foot of the rail, the middle portion being supported on top of the rail at the closed end of the slot 3.

Having thus described the invention, what is claimed as new is—

1. A car-replacer having its rear portion slotted to embrace opposite sides of a rail and provided with pendent lugs to engage over the heads of spikes driven into a tie for preventing slipping, substantially as set forth.
2. A car-replacer having a longitudinal slot extended inward from its rear end and having the corner portions of the wings bordering upon the slot cut away to clear the foot of the rail, and lugs pendent from the rear portion of the device adjacent to and upon opposite sides of the said slot for engagement with the

heads of spikes to prevent slipping of the device, substantially as set forth.

35

3. A car-replacer of approximately V form having a longitudinal slot extended forward from the rear end, a vertical flange along one edge, and a guard at the opposite edge, said guard being flattened upon its top side and gradually widened toward its front end, a space being provided between the front ends of the flange and guard and the replacer being adapted to be supported solely at its front end by means of the rail and at its rear end by a tie, substantially as set forth.

40

4. The herein-described car-replacer of approximately V form and longitudinally curved and having a slot extended forward from its rear end to form wings of different widths, a flange and guard extended upward from the longitudinal edges of the device, ribs, and flanges pendent from the device, the inner flanges being straight and parallel and adapted to embrace opposite sides of the rail, and lugs pendent from the rear portion of the wings and located upon opposite sides of and adjacent to the said slot, to engage over the heads of spikes driven into a tie, substantially as set forth.

45

In testimony whereof I affix my signature in presence of two witnesses.

OLIVER WARREN JOHNSON. [L. S.]
